UNITED STATES PATENT OFFICE.

ARCHER H. HARRIS, OF BARBERTON, OHIO, ASSIGNOR, BY MESNE ASSIGNMENTS, TO THE FAFNIR BEARING COMPANY, OF NEW BRITAIN, CONNECTICUT, A CORPORATION OF CONNECTICUT.

SHACKLE FOR VEHICLE SPRINGS.

Original application filed December 9, 1920, Serial No. 429,312. Renewed August 5, 1922, Serial No. 579,949. Original No. 1,474,361, dated November 20, 1923. Application for reissue filed August 7, 1925. Serial No. 48,906.

This invention relates to shackles for vehicle springs, and more especially the laminated supporting springs of automobiles.

The object of my invention is to provide a shackle of such construction that the wear or friction at the connections of the shackle with the spring and supporting element, resulting from the compression and rebound of the spring, is minimized; and that the ready adjustment of the members of the shackle which are subjected to end thrust, can be effected in order to take up wear and thus prevent "side slap" of the spring.

Accordingly my invention consists in various novel features of construction and combinations of parts which will be hereinafter described and claimed.

In the drawings—

Figure 1 is an end elevation, partly in vertical section, of a shackle embodying the principle of my invention.

Fig. 2 is a vertical section of the construction, as on the line of 2—2 of Fig. 1.

Fig. 3 is a vertical section through one of the antifriction bearings of the shackle, as on the line 3—3 of Fig. 1.

Referring to the drawings, 10 designates a supporting element, such, for example, as one end of a side bar of an automobile frame; and 11 designates a portion of a laminated spring which is flexibly connected at one end, 12, to the frame bar by my improved shackle. This shackle comprises two substantial side members 13 which are supported in spaced parallel relation to each other, and are arranged to embrace the bar 10 and also the end of the spring. In the present instance the shackle is illustrated as connecting the outer end of the spring with the outer end of the frame bar, but the shackle can, of course, be employed to connect the opposite end of the spring with the body of the frame bar. In fact, in practice, two shackles are employed for the respective ends of the spring.

The side members are maintained in spaced relation to each other by upper and lower cross-pins, preferably constituted by bolts 14, which are freely encircled by sleeves or bushings 15 interposed between the two members, the nuts 16 which are

screwed on one end of the bolts, bearing against the outer face of the proximate side member. The upper bushing is fast in the end (or body) of the bar 10 so as to provide a mounting attachment therefor, and the lower bushing is fixedly held in the end coil 12 of the spring. The respective ends of each of these bushings extend outward somewhat beyond the adjacent bar or spring, as at 17, and to each projecting end of a bushing is affixed the ring section 18 of a ball or roller bearing. This section encircles a complementary bearing section constituted by a ring 19 on a boss 20 on the inner side of the adjacent member. In the present instance the sections 18, 19 comprise cone rings for roller bearings, the anti-friction rollers whereof are indicated at 21.

The bolts 14 not only hold the side members of the structure in alinement, but by means of the nuts 16 adjustment of the sections 19 of the respective roller bearings in accurate relation to the sections 18 can be readily effected in order to take up wear, as occasion may require. Such bearings permit free and easy oscillations, relative to each other, of the assembled elements comprising the bar, the spring and the shackle.

It is to be particularly noted that neither of the bushings 15 comes in contact with the adjacent bolt 14 nor with the side members 13, and that therefore the said bolt is not subject to friction or to wearing action on account of the oscillation of the shackle, but, instead, the stress is confined solely to the associated cones and rollers. Hence the wearing action between the moving parts of the shackle and its adjuncts is reduced to a minimum, and, at the same time, provision is had whereby the roller bearings can be adjusted longitudinally of the bolts in order to take up wear in the said bearings, and thus effectually preventing so-called "side slap" of the spring with its attendant rattling.

I preferably provide each of the bearing sections 18 with an annular lubricating packing 22 which serves to retain grease in, and to exclude sand or water from the bearing.

In previous types of shackles wherein the

crossbolts, or pins, constituted the bearings for the bushings, it was necessary to apply a lubricant not only to the contact points of the associated bolts and bushings but also between the said bushings and the side members of the shackle. This was a difficult and unreliable operation owing to the relatively slight oscillation of the shackle, and also to the entrance of sand and water between the 10 side members and the bushings. Moreover, rapid wear, due to end thrust, took place between the bushings and the side members, thus allowing lateral movement of the spring with its attendant rattling. These objections 15 are entirely eliminated by a shackle construction embodying my invention.

It is to be understood that I do not limit my invention to the exact details of construction herein disclosed, as the same may 20 be modified within the principle of my invention and the scope of the appended claims.

I claim:—

1. In a shackle, a pair of side supporting 25 members, a pin element connecting said members in spaced parallel relation to each other, a bushing loosely encircling said pin element, a spring having one end interposed between the side members and fixed to the 30 bushing, and bearings for the respective ends of the bushing, each of said bearings comprising two complementary sections with antifriction members therebetween, one of said sections being fast on the adjacent 35 end of the bushing and the other section being fast on the proximate supporting member.

2. In a shackle, a pair of side supporting 40 members, a pin element comprising a bolt adjustably connecting said members in spaced parallel relation to each other, a bushing encircling said bolt and spaced therefrom, a spring having one end interposed between the side members and fixed 45 to the bushing, and bearings for the respective ends of the bushing, each of said bearings comprising two complementary sections with antifriction members interposed therebetween, one of said sections being fast on the adjacent end of the bushing and the other section being fast on the proximate supporting member.

3. In a shackle, a pair of side supporting 55 members, a non-rotatable pin element connecting said members in spaced parallel relation to each other, a bushing loosely encircling said pin element, a spring having one end interposed between the side members and fixed to the bushing, the respective 60 ends of said bushing extending beyond the spring, and bearings for said extending ends, each of said bearings comprising two complementary sections with antifriction members therebetween, one of said sections being fast on the adjacent end of the bushing and

the other section being fast on the proximate supporting member.

4. A shackle comprising two side supporting members, a non-rotatable pin element connecting said members in spaced parallel 70 relation to each other, an oscillatory mounting attachment loosely encircling said pin element, and bearings for the ends of the said attachment, each of said bearings comprising two complementary sections with 75 antifriction members therebetween, one of said sections being fast on the adjacent end of the attachment and the other section being fast on the proximate supporting member. 80

5. The combination with a vehicle frame and a laminated supporting spring therefor, of a shackle flexibly connecting one end of the spring to the frame, said shackle comprising two side supporting members, non-rotatable pin elements connecting said members in spaced parallel relation to each other, bushings loosely encircling said pin elements, one of said bushings being fast in the frame element and the other bushing 90 being fast to one end of the spring, and bearings for the respective ends of each of said bushings, each of said bearings comprising two complementary sections with 95 antifriction members therebetween, one of said sections being fast on the adjacent end of the bushing and the other section being fast on the proximate supporting member.

6. In a shackle, a pair of side supporting 100 members, a pin element connecting said members in spaced parallel relation to each other, a bushing loosely encircling said pin element and providing a mounting attachment, bearings for the respective ends of the said bushing, each of said bearings comprising two complementary sections with 105 antifriction members therebetween, one of said sections being fast on the adjacent end of the bushing and the other section being fast on the proximate supporting member, 110 and annular lubricating members encircling the respective bearing sections on the bushing.

7. In a device of the class described, the combination of a frame member, a spring, and a connection therebetween comprising tubular supports projecting from the eye of the spring and carrying conical bearing members on their ends, conical bearing members through which the frame is supported cooperating with the first mentioned bearing members, and anti-friction rollers between said bearing members. 115

8. In a device of the class described, the combination of a frame member, a spring, and a connection therebetween comprising tubular supports projecting from the eye of the spring and carrying conical bearing members on their ends, conical bearing members through which the frame is sup- 120 125 130

ported cooperating with the first-mentioned bearing members, means for adjusting the relation of the cooperating bearing members, and anti-friction rollers between said 5 cooperating bearing members.

9. In a device of the class described, the combination of a frame member, a spring, and a connection therebetween comprising supporting means non-rotatably arranged in 10 the eye of the spring and projecting therefrom, conical bearing members on said supporting means, supporting means on said frame, conical bearing members on the last-mentioned supporting means, and shackle 15 means having conical bearing members cooperating with the above-mentioned conical bearing members and through which said frame is connected with said spring, and anti-friction rollers between said bearing 20 members.

10. In a device of the class described, the combination of a frame member, a spring, and a connection therebetween comprising supporting means non-rotatably arranged in 25 the eye of the spring and projecting therefrom, conical bearings on said supporting means, supporting means on said frame, conical bearing members on the last-mentioned supporting means, and shackle means having 30 conical bearing members cooperating with the above-mentioned conical bearing members and through which said frame is connected with said spring, and anti-friction rollers between said bearing members.

35 11. In a device of the class described, the combination of a frame member, a spring having an eye at one end, tubular supporting means non-rotatably arranged in the eye of the spring and projecting from the sides 40 thereof, anti-friction bearings carried by the projecting portions of said tubular means, members having connection with said frame and cooperating with said bearings to transmit the frame load to the bearings, and 45 a bolt loosely arranged in said tubular means and cooperating with said members to maintain them in their normal relation to said bearings.

50 12. In a device of the class described, the combination of a frame member, a spring having an eye at one end, tubular supporting means non-rotatably arranged in the eye of the spring and projecting from the sides thereof, anti-friction bearings having one 55 of their races carried by the projecting portions of said tubular means, members connected with said frame member and cooperating with the other races of said bearings to transmit the load thereto and a bolt extending 60 through said tubular means and said members to maintain the parts in their normal relation.

65 13. In a device of the class described, the combination of a frame member, a spring having an eye at one end, tubular support-

ing means non-rotatably arranged in the eye of the spring and projecting from the sides thereof, anti-friction bearings having one of their races carried by the projecting portions of said tubular means, an eye in 70 said frame member, tubular supporting means non-rotatably arranged therein and projecting from the sides thereof, anti-friction bearings having one of their races carried by the projecting portions of the last-mentioned tubular means, shackle members 75 cooperating with the other members of said bearings to transmit the load from the frame to the spring, and bolts extending through said eyes and maintaining the parts in their 80 normal relation.

14. In a device of the character described, supporting means to be secured to a vehicle spring, supporting means to be secured to a vehicle frame, shackle members at opposite 85 sides of said supporting means for securing the spring and frame together, anti-friction bearing members interposed between said supporting means and said shackle members, the bearing surfaces for said anti-friction 90 bearing members on said supporting means and on said shackle members being inclined whereby lateral and end thrust is taken by said anti-friction bearing members, and means for securing said shackle members together. 95

15. In the combination defined in claim 14, said shackle members being bodily movable toward and from each other for permitting adjustment of the bearing surfaces 100 and the anti-friction bearing members.

16. In the combination defined in claim 14, the bearing surfaces on said shackle members extending inwardly and within the complementary bearing surfaces on said supporting means. 105

17. In a device of the character described for securing a vehicle frame to a vehicle spring, shackle plates pivotally secured to one of said members, hollow means on the other of said members, anti-friction bearing members interposed between said hollow means and said shackle plates and means passing through said hollow means for holding said shackle plates in position. 110 115

18. In a device of the character described, for connecting a vehicle frame to a vehicle spring, shackle plates pivotally secured to one of said members, said other member having anti-friction raceways thereon, anti-friction bearing members interposed between said raceways and said shackle plates, the bearing surfaces on said shackle plates and said raceways being inclined whereby radial and end thrusts may be taken by said anti-friction bearing members. 120 125

19. In a device of the character described, for connecting a vehicle frame to a vehicle spring, and including side members on said frame, means secured to the spring and lo- 130

cated between said side members, anti-friction bearing members interposed between bearing surfaces on said means and said side members, said surfaces being inclined where-
5 by both radial and end thrusts may be taken by the anti-friction bearing members.

20. In a device of the character described for connecting a vehicle frame to a vehicle spring, side supporting members on the frame and extending over the end of the spring, a raceway member on the inside of each of said side supporting members, race-
10 way means at opposite sides of said spring and complementary to said raceway mem-
bers on said side supporting members, and anti-friction bearing members interposed between said complementary raceways, said raceways being inclined whereby both radial and end thrust loads are taken by said anti-
15 friction bearing members.

21. In the combination defined in claim 20, said side supporting members being pivotally secured on said frame.

22. In the combination defined in claim 25 20, said raceway members on said side sup-
porting members extending inwardly toward the spring and into the raceway means on said spring.

23. In a device of the character described, 30 the combination of a frame member and spring each having an eye therein, side

members for connecting said frame and spring, complementary race members asso-
ciated respectively with the frame, spring and side members, anti-friction bearing 35 members interposed between the race members on said side members and said spring and frame, and means passing through one of said eyes for holding said side members and anti-friction bearing members in proper 40 relation to each other.

24. In the combination defined in claim 23, and means passing through the other of said eyes and serving to hold said side members and anti-friction bearing members 45 in proper relation to each other.

25. In a device of the character described for connecting a vehicle frame to a vehicle spring, side supporting members on the spring and extending over the frame, a race-
50 way member on the inside of each of said side supporting members, raceway means at opposite sides of said frame and comple-
mentary to said raceway members on said side supporting members, and anti-friction 55 bearing members interposed between said complementary raceways, said raceways being inclined whereby both radial and end thrust loads are taken by said anti-friction bearing members.

ARCHER H. HARRIS.
